UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 21,101, dated October 6, 1891.

Application filed September 14, 1891. Serial No. 405,701. Term of patent 14 years.

To all whom it may concern:

Be it known that I, HERMAN IHLENBURG, a citizen of the United States, and a resident of Philadelphia, Pennsylvania, have invented a 5 Design for a Font of Printing-Type, of which the following is a specification.

My design for a font of printing-type is fully illustrated in the accompanying typographical impression.

10 The general feature of the design is the peculiar lower termination of the majority of the letters of the upper case, the letters of the font being light, but having a solid face. Each of the letters of the upper case have 15 their upper portions on or about the same line, while the lower termination of the above-mentioned letters differ. The letters F, G, I, O, U, V, W, X, Y, and Z terminate on the lower line, while the other letters have exten-

sions which are below the line. The letters 20 A, C, E, H, K, L, M, P, Q, R, and I have curved ends, which extend to the right, and the letters B, D, J, and S have curved ends extending to the left. The cross-bars of the letters A, B, H, and K are curved. 25

The lower-case letters, as well as the numerals, are in keeping with the general design.

I claim—

The design for a font of printing-type, substantially as described, and as shown in the 30 accompanying typographical impression.

In testimony whereof I have signed my name to this specification in the presence of two subscribing witnesses.

HERMAN IHLENBURG.
